DRIVING MECHANISM FOR KNITTING
NEEDLES

Jörgen P. Lindholm, Stockholm, Sweden, assignor
to Lindan Electro, Inc., a corporation of New
York

Application August 3, 1946, Serial No. 688,385
In Denmark August 22, 1942

Section 1, Public Law 690, August 8, 1946
Patent expires August 22, 1962

2 Claims. (Cl. 66—1.5)

1

This invention relates to driving mechanism for knitting-needles, especially of the kind used for repairing knitted hosiery.

One object of the invention is to provide a driving mechanism of the kind referred to which is adapted to be mounted on a sewing machine and to be driven thereby.

Another object of the invention is to provide a driving mechanism of the kind referred to, comprising an air-pump for supplying motive power to the knitting-needle and provided with means for securing the pump to the spool holder on a sewing machine, and with a driving roller adapted to co-operate with the periphery of the balance wheel of the sewing machine.

Other objects and features will appear as this description proceeds, reference being had to the accompanying drawing, in which

Figure 1 shows a driving mechanism in accordance with this invention mounted on the sewing machine,

Figures 2 and 3 are sectional views of details, and

Figure 4 a modification.

In Figure 1 10 is a sewing machine having a balance wheel 12 adapted to be driven by means of a hand crank 14 or through a belt drive by means of a motor or pedal.

The driving mechanism of a knitting-needle (not shown) is mounted on the sewing machine in a manner which will now be described. The knitting-needle may be of the type adapted to be driven by compressed air supplied by a piston pump. As such knitting-needles are known per se, the needle need not be described in detail.

The driving mechanism of the knitting-needle comprises an air pump, the piston of which (not shown) is connected as by means of a connecting rod 18 with a crank 20 associated with a driving roller 22 which is mounted for rotation in a bearing 22a supported by an extension 23 of the pump cylinder 16. The pump is supported on the sewing machine in such position that the driving roller 22 engages the periphery of the balance wheel 12 so as to be driven thereby to cause the pump 16, which is connected with the knitting-needle through a hose 24, to impose pulsating air pressure on the knitting-needle.

The pump cylinder 16 is rigidly connected with an arm 26 which is slotted over the greater part of its length. As clearly shown in Figure 1, the arm may be made of thick wire which is bent back on itself, leaving a space between its two branches. The arm 26 is provided with two sliding members 28 and 30 which are adapted to be

2

adjusted along the length of the arm and which are provided with bores adapted to be received in spool holders 32 and 34 respectively of the sewing machine. The members 28 and 30 are secured to said yarn holders by means of thumbscrews 36 and 38 respectively.

The shape of the members 28 and 30 appears from Figures 2 and 3. Each member 28 or 30 has a height corresponding to the width of the slot of the arm 26 and is at one side of the arm provided with a flange 40 adapted to engage the face of the arm.

Instead of securing the arm 26 to both yarn holders of the sewing machine, a slidable rod 42 may be mounted in one of the members 28, 30 which terminates at its lower end in a bifurcated member 44 adapted to be supported upon the upper side of the sewing machine. Through this measure, the device will also be applicable to sewing machines having one spool holder only.

In order to ensure firm engagement between the driving roller 22 and the balance wheel 12 of the sewing machine, a coil spring 46 may be inserted between the member 28 and the member 48 secured to the spool holder 32 as by means of a thumb-screw 50, as shown in Figure 4. In this instance the member 28 is freely slidable on the spool holder 32. In this embodiment the members 28, 43 and the member 30 are threaded over the spool holders 32, 34 respectively until the roller 22 engages the circumference of the balance wheel 12. Now the member 30 is secured to the spool holder 34 by means of the thumbscrew 38 and the member 48 is urged a small distance in an upward direction so as to compress the coil spring 46 whereby the roller 22 is urged firmly against the circumference of the balance wheel 12.

By suitably adjusting the compression of the spring 46, the pressure between the roller 22 and the wheel 12 may be so adjusted as to ensure driving of the pump 16 without unnecessary strain upon the balance wheel.

The device described is of very simple construction and comprises relatively few parts so that it may be manufactured at low costs in mass production.

Further, the device presents the advantage that it can be easily fitted to a sewing machine without the necessity of removing any part of the latter. During operation of the device, the balance wheel of the sewing machine may be disconnected from the other movable members of the machine in order to facilitate operation and

to avoid unnecessary wear of the said other members of the machine.

I do not wish to confine myself to the embodiments described and shown in the drawing, which may be modified in various respects within the scope of the appended claims.

I claim:

1. For use with a sewing machine having a balance wheel and one or more spool holders, a driving mechanism for knitting needles, comprising driving means adapted to co-operate with the periphery of the balance wheel, an arm adapted to extend along the upper side of said machine, and slidable clamping members on said arm adapted to be secured to the spool holders 15 of the sewing machine.

2. For use with a sewing machine having a balance wheel and one or more spool holders, a driving mechanism for knitting needles, comprising a driving roller adapted to co-operate 20

10
15

with the periphery of the balance wheel, an arm adapted to extend along the upper side of said sewing machine, a member on said arm adapted to be secured to one spool holder of said machine, and yieldable means associated with said arm and adapted to be secured to another spool holder of said sewing machine for urging said driving roller towards said balance wheel.
